ATTORNEY

UNITED STATES PATENT OFFICE

162,791

DRAIN PAN

Mike Citero, Los Angeles, Calif.

Application May 19, 1949, Serial No. 2,745

Term of patent 14 years

(Cl. D44—29)

To all whom it may concern:

Be it known that I, Mike Citero, a citizen of the United States, residing at Los Angeles, county of Los Angeles, and State of California, have invented a new, original, and ornamental Design for a Drain Pan, of which the following is a specification, reference being had to the accompanying drawing, forming part thereof.

Fig. 1 is a perspective view of a drain pan, showing my new design.

Fig. 2 is a medial section of the pan, taken through the lip thereof, and

Fig. 3 is a front elevational view of the same.

I claim:

The ornamental design for a drain pan, as shown.

MIKE CITERO.
